UNITED STATES PATENT OFFICE.

ARTHUR E. FREEMAN, OF TORONTO, ONTARIO, CANADA.

CHOCK-FITTING FOR BOATS.

1,322,003.

Specification of Letters Patent.

Patented Nov. 18, 1919.

Application filed March 22, 1918. Serial No. 223,974.

To all whom it may concern:

Be it known that I, ARTHUR E. FREEMAN, a citizen of the United States of America, and resident of the city of Toronto, county 5 of York, Province of Ontario, in the Dominion of Canada, have invented certain new and useful Improvements in Chock-Fittings for Boats, described in the following specification and illustrated in the accompanying drawings, that form part of the same.

The principal objects of the invention are to devise a chock fitting which will hold the boat securely in place in the chocks and 15 upon being operated to release the boat will ease it off from the chocks in such a manner as to prevent the boat being damaged.

A further and important object is to devise a chock fitting which will have no tendency to release through the pressure of the 20 load but it may be operated to release the load with very great ease.

A still further object is to provide a simple form of gripe holder to operate in 25 conjunction with the means for holding the keel of the boat.

The principal feature of the invention consists in the novel construction and arrangement of a rotatable member upon 30 which the keel is supported, whereby the keel is held securely locked and upon the rotation of said member the keel is moved definitely in an outward incline, and whereby the gripes are released simultaneously with 35 the operation of the keel release.

In the accompanying drawings, Figure 1 is a perspective view of my improved chock fitting shown from the inboard side.

Fig. 2 is a side elevational view.

40 Fig. 3 is an elevational view of the inboard end of the fitting.

Fig. 4 is an end elevational view of the outboard end of the fitting shown in the locked position.

45 Fig. 5 is an end elevational view of the outboard end of the fitting shown in the position of release.

Fig. 6 is an outboard elevational end view shown in the extreme position of release.

50 In the drawings, the block 1 which is shaped to fit the curvature of the underside of the boat at one side of the keel is rigidly secured to the deck of the ship, the outboard end 2 thereof being cut perpendicular.

55 3 is a bracket rigidly secured to one side

of the block 1 and to the deck having a horizontally arranged journal bearing 4 therein.

5 is a bracket arranged at the inboard end of the block and on the same side as the bracket 3 having the journal bearing 6.

60 A bar 7 which may be hollow in the form of a piece of iron pipe is journaled in the bearings 4 and 6 and extends beyond said bearings.

A cam member 8 is eccentrically secured 65 upon the outboard end of the bar 7, the inner face thereof bearing against the outer face of the bracket 3. This cam member is of eccentric formation, the contour of its inner face adjacent to the bracket 3 being substantially oval, one side having a lug extension 9, the top surface 10 of which is flat.

The keel of the boat rests upon the surface 10 when the device is in the position shown 75 in Figs. 1, 2, 3 and 4 and as the flat surface extends past the pivot center the weight of the load holds the member locked as is clearly shown in Fig. 4.

A finger-shaped lug 11 extends upwardly 80 from the outward side of the flat surface 10 and engages the side of the keel of the boat as is clearly illustrated in Figs. 1, 2, 3 and 4, and locks the boat securely in position. The oval-shape of the cam member 8 at 85 the inboard side is merged into an outwardly sloping beveled surface 12 which is arranged substantially in right angular relation to the top flat surface 10.

It will thus be seen that a quarter turn of 90 the cam member first withdraws the finger lug 11 from engagement with the keel of the boat and the sloping surface is then brought gradually under the keel and imparts to it a definite outward push and as the surface 95 12 is beveled with a definite outward slope it carries the boat in an outboard direction and in such a way that the bilge of the boat will be moved clear of the engaging surface of the block 1. The movement of 100 the keel in slipping off the beveled face of the cam is more than sufficient to take up the average stretch or slack in the falls, consequently the boat is eased off into the falls with a very gentle action and no lifting of the boat is required.

The bar 7 is rotated by means of a cranked lever 13 which is keyed to the inner end and held in the locked position by a ring 14 carried on the bracket 15 secured to 110

the block 1. A spur 16 is formed upon the boss of the lever 13 and when the lever is in the upright position as shown in Figs. 1 and 3 the spur projects downwardly and forms a holder for the boat gripe which is not shown in the drawings but which is of very common use, being merely a rod or chain secured to the gunwale of the boat to hold the boat securely upon the chocks.

10 It will be seen that upon the release of the lever 13 and its movement to swing the cam 8 the spur is swung upwardly and automatically releases the gripe.

15 A crank 17 is secured upon the extreme inner end of the bar 7 and to this crank is secured a bar 18 which may be connected to the companion chock fitting at the opposite end of the boat so that by the operation of the one lever both ends of the boat will 20 be released simultaneously.

25 It will be noted particularly that when the boat is in place the keel rests upon the horizontally arranged top flat surface of the cam member and there is no tendency whatever for the device to release itself, but a very slight pressure upon the operating lever will cause it to rotate and effect the release.

30 The peculiar shape of the cam member is such that as the flat top surface extends slightly beyond the center and retains the device locked, upon rotation it effects a slight lift which results in the freeing of the boat from sticking either upon the cam 35 or chock. The oval shape then recedes and allows the boat to settle against the sloping block 1 which starts a wedging action and this action is taken up and continued by the bringing of the sloping surface 12 immediately beneath the keel.

40 What I claim as my invention is:—

1. A chock fitting for boats, comprising, a block engaging the inboard side of the boat, a member rotatably arranged at the 45 outboard side of said block on an axis transverse to the keel of the boat and supporting the keel and having an upward extension engaging the outer side of the keel, said rotatable member being adapted on rotation to effect the outward movement of the boat from the block and means for rotating said member to release the boat.

50 2. A chock fitting for boats, comprising, a block engaging the inboard side of the boat, a rotatable member supported at the outboard side of the block and having its upper surface engaging the full width of the keel and an upwardly extending lug engaging the side of the keel to lock the boat

60 in place, said member also having an outwardly and downwardly sloping surface, and means for rotating said member to disengage the lug from the keel and to bring the sloping surface into contact with the bottom of the keel to effect the release of 65 the boat.

3. A chock fitting for boats, comprising, a block engaging the inboard side of the boat, a rotatable member eccentrically supported at the outboard side of said block 70 and having a horizontal portion normally engaging and supporting the bottom of the keel and a lug projection at the outer side engaging the side of the keel, the perimeter of said eccentric member merging from the 75 horizontal surface into an outwardly and downwardly sloping surface, and means for rotating said eccentric member to withdraw the locking lug from engagement with the keel and to move the sloping surface 80 underneath the keel.

4. A chock fitting for boats, comprising, a block, engaging the inboard side of the boat, a rod supported in journals secured at the side of said block, a rotatable member eccentrically secured upon the outboard end of said rod and having a projection adapted to engage the outboard side of the 85 keel and formed with a sloping surface adapted on the rotation of the rod to move 90 beneath the keel, and an operating lever rigidly secured to the inboard end of said rod.

5. A chock fitting for boats, comprising, a block engaging the inboard side of the boat, a rod journaled at the side of said block, a member secured to the outboard end of said rod and supporting the keel and adapted on rotation to release the keel, a lever rigidly secured to the inboard end of 95 said rod and having a gripe hook formed thereon, and means secured to the block for locking the lever.

6. A chock fitting for boats, comprising, a block engaging the inboard side of the boat, a rotatable member eccentrically supported at the outboard side of said block and having a horizontal portion normally engaging and supporting the bottom of the keel and a lug projection at the outer side engaging the side of the keel, the perimeter of 105 said eccentric member being formed with a reducing radius and the surface merging from the horizontal to an outwardly and downwardly sloping plane effecting the lowering of the boat and the subsequent outward guidance of the keel.

110 ARTHUR E. FREEMAN.
